CASTER WHEEL

Alfred L. Von Tersch, Clarinda, Iowa, assignor to Lisle Corporation, Clarinda, Iowa, a corporation of Iowa

Filed May 20, 1965, Ser. No. 85,381

Term of patent 14 years

(Cl. D10—6)

FIG. 1 is an edge view of a caster wheel, showing my new design;

FIG. 2 is a face view thereof, looking in the direction of the arrow 2 adjacent FIG. 1;

FIG. 3 is a sectional view on the line 3—3 of FIG. 2;

FIG. 4 is a face view opposite that shown in FIG. 2;

FIG. 5 is a perspective view, and

FIG. 6 is a sectional view on the line 6—6 of FIG. 3. The dotted line showing is for illustrative purposes only.

I claim:

The ornamental design for a caster wheel, substantially as shown and described.
